John C. Hennigelman
Inventor

The subject referred to in this Letter Patent and making part of the same containing a description in the words of the said Mr. Hennigelman himself of his improvement in the Truss for the cure of Sciatica.

To all to whom these presents shall come. We it known that I, John C. Hennigelman of the City and County of Philadelphia and State of Pennsylvania have invented a new and useful improvement in an Truss for the cure of sciatica for which Letter Patent was granted to me on the 21st day of July 1831, and which I style Hennigelman's improved Truss Pat and that the following is a full and exact description of the construction and operation of the same as invented or improved by me. My improvement consists in the construction of the pad which is as follows. A circular or oval disk is made of strong tin, sheet copper, brass or other material of sufficient the same elasticity and firmness of say 3 inches diameter, a portion of the surface at the centre, about equal in diameter to half the diameter of the disk, is by means of dies, punches or any other convenient means punched up or raised so as form a spherical or spherical concavity towards the front, a flat side of the disk which is to lie next to the patient, and a corresponding concavity on the back side of which the concave angular surface or ring is punched in a similar manner, concave on the front side & convex on the back. These inflections may all be made in one operation by dies such as are in ordinary use. To the center of the cavity in the back is secured by soldering a small hollow brass or metal cylinder say $\frac{1}{4}$ of an inch in diameter and $\frac{1}{2}$ of an inch long, iron or copper, this cylinder is intended to receive the attachment which secures the pad to the bow or spring of the truss as hereinafter described. The middle or back being thus formed I may take two small pieces of wood or other material which may be pieces of bent cardboard or gun stock or any sufficient article being sufficient with the concave

8851

concupisces of the disk, to meet all around on the outer circumference of the latter an opening being also cut in the back piece for the insertion of the cylinder, the disk being now placed between these sheets they are joined closely in a pair of dies with cometics and concavities nearly corresponding with the impressions of the disk (except a depression for the cylinder) and sufficiently larger to receive the additional thickness of the sheets and to mould a full concave edge or ring beyond the circular cavity of the front of the pad the air having been previously heated to a proper degree, by which means in a few minutes the edges of the gun elastic sheet are firmly united together and the pad containing the figure and impression by the air, is ready for attaching to the bow which is done in the following manner. The cylinder having been mentioned is closed by a circular head or plate having a hole in its centre and furnished with a screw thread at its circumference which screws or takes into a corresponding thread in the upper part of the cylinder. A strong metallic pin or shaft passes through the hole in this plate, the part within the cylinder having a broad circular head nearly of equal diameter with the cylinder which rests or bears on a spiral steel spring dipping loosely into the cylinder, the other end of the pin projecting about $\frac{1}{8}$ of an inch beyond the plate with a screw hole in its centre to receive the screw which attaches the bow or spring of the trap as follows. The end of the bow or spring which may be $\frac{1}{8}$ an inch broad and thin as the required degree of strength will permit being introduced into a slot or mortice made in an oblong button or piece of brass, a screw is passed through the button and spring which takes in the end of the pin above mentioned, and confining the whole together, the length of the slot allowing a slight lateral motion to the bow, which in connection with the action of the spiral spring upon which the head of the pin bears, forms a sort of universal joint, and admits of an easy rolling motion of the bow or pad without the latter being in the least displaced or its pressure abated. In the pad for general use the attachment is the same & only differs from the concave hair shaded pad in common use (shaded with a cross) by being formed of dies as herein described of a

and will come with your clothes without stuffing. This trap is to be applied in the usual manner, the dimensions of the pad as to the size of its concavity being varied to suit the circumstance of the case and the indications of the disease, the regulation of which is left to the judgment of the practitioner or the patient. Now all that I now claim as my invention and improvement and for which I wish Letters Patent is the mode of placing the oval side of the pad between the two sheets of acetate or paper and matrix as herein described and not forth instead of placing it as formerly before them, and dispensing with a covering of silk, leather, or any other substance whatever, thereby rendering the pad more elastic, more simple and durable, and perfectly easy to be cleaned without injury. In testimony that the foregoing is a true specification of my said improvement, I have hereunto set my hand at the city of Washington this 15th day of May 1835
